UNITED STATES PATENT OFFICE.

WILLIARD OSCAR LONG, OF MANSFIELD, OHIO.

HORSESHOE-CALK AND FASTENER.

No. 813,655.

Specification of Letters Patent.

Patented Feb. 27, 1906.

Application filed August 25, 1905. Serial No. 275,830.

To all whom it may concern:

Be it known that I, WILLIARD OSCAR LONG, a citizen of the United States, residing at Mansfield, in the county of Richland and State of Ohio, have invented a new and useful Horseshoe-Calk and Fastener, of which the following is a specification:

This invention relates to improvements in horseshoe-calks and the means for fastening the same, and has for its object to provide a simply-constructed and easily-applied device of this character which may be attached to any of the various sizes and forms of horse-shoes in use and by means of which the calks 15 may be securely locked in position on the shoes, while at the same time readily detachable, when required, without removing the shoes from the hoofs of the horses.

With these and other objects in view, which will appear as the nature of the invention is better understood, the same consists in certain novel features of construction, as hereinafter fully described and claimed.

In the accompanying drawings, forming a part of this specification, and in which corresponding parts are denoted by like designating characters, is illustrated the preferred form of embodiment of the invention capable of carrying the same into practical operation.

In the drawings, Figure 1 is a perspective view from beneath of a horseshoe with the improved calks and their fastening means applied. Fig. 2 is a sectional detail illustrating the manner of constructing and applying the improved device. Fig. 3 is a sectional detail of the parts shown in Fig. 2 viewed from another point. Fig. 4 is a perspective view of the locking-plate, and Fig. 5 is a perspective view of one of the improved calks detached. Fig. 6 is a view similar to Fig. 3, illustrating a modification in the construction.

The improved device may be applied to any size or form of horseshoe and may be employed in connection with both the heel and toe calks; and for the purpose of illustration is shown applied to all the calks on the shoe, (represented at 10.)

The improved calks 11 are in L shape with one arm 12 sharpened and the other arm provided with a bolt-aperture 13, and the shoe 10 is provided at the points where the calks are to be attached with threaded apertures 14 to receive the cap-screws 15, where-

by the calks are secured in position upon the shoe. The toe-calk member will preferably be in one single piece with two bolt-apertures to receive two of the cap-screws, as in Fig. 1, while the heel-calks are of smaller length or corresponding to the width of the heel portions of the shoe.

A locking device is provided for each of the cap-screws, consisting of a plate 16, provided with a bolt-aperture and with the material of the plate next to the arm 12 of the calk greater in length than the distance between the aperture 13 in the calk and the adjacent face of the arm 12 of the calk, as shown at 20, so that when the locking-plate is placed in position upon the calk the aperture 17 in the plate will overhang the aperture 13 in the calk. By this arrangement when the cap-screw is turned home into the threaded aperture in the shoe the head 15 of the bolt bears upon the plate and compresses it against the base portion 11 of the calk and likewise bends the edge 19 against the projecting portion 12 of the calk, as shown more clearly in Fig. 2, thus causing the plate to be firmly compressed against the bolt transversely, while at the same time exerting a strong force outwardly against the head of the bolt by the reaction of the plate and effectually preventing retrograde movement of the bolt. As an additional holding means one or more corners of the locking-plates may be bent against the sides of the head portion of the bolt, as at 18.

Having thus described the invention, what is claimed is—

1. A horseshoe and a horseshoe-calk provided with aligned bolt-apertures and a projection extending from said calk, a locking-plate bearing against said calk and provided with an intermediate bolt-aperture, the material at one side of the aperture in said plate being of greater distance than the distance between the aperture in said calk and the projection on the same, and a bolt engaging said apertures and bearing by its head against said locking-plate and bending the excess material therein against the projection, the plate being thereby caused to exert a pressure transversely of the bolt and likewise outwardly against the head of the same.

2. A horseshoe and a horseshoe-calk provided with aligned bolt-apertures and a projection extending from said calk, a locking-

plate bearing against said calk and provided with an intermediate bolt-aperture, the material at one side of the aperture in said plate being of greater distance than the distance 5 between the aperture in said calk and the projection on the same, and a bolt engaging said apertures and bearing by its head against said locking-plate and bending the excess material therein against the projec-

tion, and the head further secured by bending the free end of the plate over the same.

In testimony that I claim the foregoing as my own I have hereto affixed my signature in the presence of two witnesses.

WILLIARD OSCAR LONG.
